UNITED STATES PATENT OFFICE.

CURRY ORA WALPER, OF DETROIT, MICHIGAN, ASSIGNOR OF ONE-THIRD TO FRANK A. MASLEN AND ONE-THIRD TO BERNARD E. CLARK, BOTH OF DETROIT, MICHIGAN.

BUILDING STRUCTURE.

Original application filed August 20, 1921, Serial No. 493,921. Divided and this application filed July 24, 1922. Serial No. 576,969.

To all whom it may concern:

Be it known that I, CURRY ORA WALPER, a citizen of the United States of America, residing at Detroit, in the county of Wayne 5 and State of Michigan, have invented certain new and useful improvements in Building Structures, of which the following is a specification, reference being had therein to the accompanying drawings.

10 This invention relates to a system of building construction and has for its primary object the provision of a rigid panel of substantially fireproof material to be used in place of the usual wood or metal lath and 15 rough plaster for interior walls and ceilings, or in place of the various bases upon which stucco is applied to form exterior walls.

Another object of the invention is to utilize a product hitherto considered as waste, 20 as a building material for interior or exterior use, in constructing walls resistant to heat, at a cost considerably less than that of materials now ordinarily employed.

In the preferred construction, a plastic 25 composition is used consisting of the waste product of asbestos manufacture mixed with plaster. Asbestos occurs in veins of fibrous magnesium silicate. The surrounding rock is usually of a similar composition but is 30 not so fibrous. After most of the fibrous asbestos has been removed, the rock mined therewith containing some fibrous asbestos is usually discarded and considered as waste. It is sold as "rough asbestos" or "tailings."

35 When this is crushed, the resultant asbestos somewhat resembles a mixture of asbestos and talc. Mixed with a suitable plaster, such as the ordinary "blue plaster" containing gypsum and lime, from five to fifty 40 per cent of the composition may be asbestos to form the body of a fireproof wall board.

A composition of plaster and asbestos permits nails to be driven therethrough without cracking and by the use of a nail set, 45 the heads may be countersunk for additional protection, yet the composition is so poor a conductor of heat that a three-eighths inch board of this material will prevent ignition of paper on the surface opposite a flame 50 for a longer period than an inch thickness of ordinary plaster would.

A board three-eighths of an inch in thickness molded upon a backing reinforced with transverse strips of thin sheet iron and

nailed upon ordinary wooden joists forms a 55 very rigid wall upon which a finishing coat of plaster for interior walls or of stucco for exterior walls may be applied, and such a wall complies with the requirements of a rigid building code for locations in which 60 sheet metal lathing and heavy plaster are ordinarily specified. The cost is much less than that of the ordinary wooden laths, rough coat, and finishing coat of the current building practice.

65 Another waste product of asbestos manufacture is what is known as asbestos sandings, this material being the portion removed from the surface and edges of asbestos boards by grinding or sandpapering. 70 This waste material consists of asbestos fibers and cement and is similar in its qualities to the crushed asbestos.

75 It is of course obvious that asbestos itself may be used with plaster to form a board of even better quality than that produced by the use of asbestos or asbestos sandings.

In the drawings,

Figure 1 is a horizontal section of a preferred form of reinforced board secured to 80 its supports and provided with a surface or finishing coat;

Fig. 2 is an elevation, and Fig. 3 an enlarged detail section of the structure shown in Fig. 1;

85 Figs. 4, 5 and 6, are fragmentary plan views of alternative forms of reinforcement;

Fig. 7 is a fragmentary perspective view of a modification;

Fig. 8 is a fragmentary section showing a 90 modification of the arrangement of the reinforcing fabric, and

Fig. 9 illustrates an alternative form of nailing strip.

In the embodiment illustrated in Figs. 1 95 and 2, the backing 1 is a sheet of wire cloth which may be of the kind used for fly-screens. Upon this backing, strips 2, 2, of sheet iron, which may be galvanized or otherwise rust-proofed, or cut from tin or 100 terne plate, are laid substantially parallel with each other transversely of the sheet from edge to edge, these flat strips being of a width sufficient to receive the securing nails driven therethrough into the supporting studs or joists 3, 3. The nailing strips or straps 2 are secured by spot welding directly to the wire mesh and the securing

nails 4 are driven through these straps and through the wire mesh at 5 into the studs or joists 3.

The surface of the board will be provided 5 with marks 7 which may consist of indentations of any desired form to indicate the position of the nailing strips, so that the nail may be driven through the center of the strip. These strips will of course be of 10 sufficient width to permit a reasonable amount of variation in the driving of the securing nails.

As a means of securing the nailing strips 2 firmly in place in the plastic body of the 15 boards, lugs 9 may be formed upon, or secured to the strips 2, a preferred shape being shown in Fig. 2, in which the upwardly bent member 9 is dovetailed to offer the maximum resistance to withdrawal of the member 20 from the composition 8.

The metallic reinforcement will be treated with a special heavy coating of some rust-proofing material before embedding it in the cement.

25 After the reinforcement is set in place, the plastic composition is poured over and around the strips and backing, which may rest upon any suitable support until the cement begins to set.

30 A secondary reinforcing fabric 11 is then placed upon the top. At the proper stage of setting of the plaster, pressure is applied to render the composition 8 denser and to force it into the backing 1 and reinforcement 35 11. The plastic composition passes through the meshes of the backing and of the secondary reinforcement so that the surface layer is a coating of plastic material, to which the ordinary finishing coat of plaster 40 will firmly adhere for interior work, or to which stucco will cling to form a decorative surface for exterior work.

It has been found that an open meshed but strong burlap forms a highly satisfactory reinforcement, since the plastic material passes readily through its mesh and if the burlap is treated with any of the ordinary fireproofing solutions before it is embedded in the surface of the plastic composition 45 it will resist the action of flames because of the protection afforded by the heat resisting coating containing asbestos.

After the burlap has been pressed into the wet plastic composition, a sanding coat of 50 rough gypsum is sprinkled over the surface, absorbing a sufficient quantity of water from the wet composition to adhere and to form a very satisfactory surface for the adhesion of the finishing coat which will preferably 60 be made of a fireproof composition consisting of gypsum, lime, and asbestos flour.

This board having such a large percentage 65 of asbestos is lighter than plaster for the same thickness, but since it is fireproof, a thinner coat is used. Furthermore, because

of the material being fireproof, a much lighter metallic reinforcement may be used.

The complete coating is much thinner and much lighter than plaster upon metallic lath 70 for equal fire protection.

Ceilings are thus much lighter, and by reversing the position of the reinforcement, or (which amounts to the same thing) by placing the sanding coat on the surface next to the reinforcement and using that surface 75 as the outer surface in ceilings, the plaster composition cannot fall off even in a fire, because the metallic reinforcement will support it.

In a ceiling, the resistance to pressure upward, or toward the supporting beams is not necessary, and the reinforcement may be placed near the outer or lower surface to act as a support to prevent falling of the 80 plaster.

85 Water thrown against a hot board of this composition will not cause cracking, and the anchors upon the reinforcement bind the composition together with the aid of the burlap, so that in a fire, the material will not be knocked off by a stream of water thrown by a hose.

The extra weight of the ordinary plaster 90 will tend to make it fall in case of fire sooner than the lighter material of the composition 95 board.

One of the principal objections to the use 100 of plaster boards has been the difficulty in securing a proper finish along the joists where the boards meet. Where such boards are made of paper pulp or other fibrous material, there is almost always a certain amount of swelling and shrinking with atmospheric changes, and this action produces cracks so that in some cases almost 105 every joint can be discerned.

Where the boards are made of a plastic 110 composition, there is less shrinkage, but such cracks as appear are found at places where the boards meet.

To prevent such cracking and at the same time to protect the heads of the securing 115 nails from the action of flames, I have devised the protecting reinforcement illustrated in Fig. 1.

The nails 4 are driven into the boards and countersunk as shown at 10. A strip of plaster is then run down the joist to fill in the space between the edges of the board and the recesses left by countersinking the 120 nails. Into this wet plaster, a reinforcing strip 12 of wire mesh or other suitable material is placed, the strip being of sufficient width to overlap the nail heads on both of the meeting boards. Since the ordinary 125 studding is about two inches in thickness, the wire reinforcement 12 need not greatly exceed this width. The setting of the plaster holds the reinforcing strip in place without the use of nails. The finishing coat 13 130

completely conceals the flat ridge made by the wire and plaster reinforcement along the joist and cracking is entirely prevented.

The strips 12 are preferably of wire, 5 woven as a narrow strip about two or three inches in width. It will be supplied conveniently in rolls or bundles. By weaving a special narrow strip, the danger is avoided of having projecting wire ends to interfere 10 with the working of the finished coat.

If the strips are cut from a wide piece of wire fabric the edges will preferably be folded back upon the surface of the strip. In place of a wire strip, it is evident that 15 burlap or other fabrics, or broad tapes, or even strips of suitable paper or other material resistant to tensile stresses may be used, the details of such strips forming no part of the present invention.

20 When nails are driven through a board having other than a paper surface, the heads are ordinarily left exposed and the metallic nail transmits the heat of flames to the wooden supporting beams causing a 25 rapid charring. The hot nails in the charred wood cannot resist the outward pull caused by the heavy material and the entire board pulls loose and falls, leaving a passage for the fire.

30 In the present system the nails are countersunk and a considerable thickness of plaster lies between the heads and the exposed surface. The nails cannot be reached by the flame as long as the asbestos composition

35 forming the finishing coat is intact. The metallic reinforcement and its securing nails are protected by an asbestos composition which is very resistant to heat. They will thus remain in position, holding the

40 boards in place, and maintaining a fireproof protecting layer intact over the entire surface. The long projecting anchors on the nailing strips engage firmly with the composition being interlocked with a large portion

45 of the mass and the nailing strips are welded to the wire mesh. When the nailing strip and reinforcing mesh are fastened to the supports, the plastic material cannot fall off in sheets as in the case of those forms of 50 board in which the sole support of the composition is an inflammable paper surface.

It is evident that many modifications may be made in the structure and arrangement of the reinforcing means without departing 55 from the spirit of the invention. The reinforcing material used as a backing may consist of expanded metal lathing having flat inextensible portions 14 and intermediate open portions 15 as shown in Fig. 4.

60 Another suitable reinforcement is that shown in Fig. 5, in which a wide mesh screen 16 has flat nailing strips 17 woven into the body of the fabric at suitable intervals. Instead of the flat strips 17 the woven fabric

65 together at intervals to form closely woven bands as indicated at 18, such bands acting as nailing strips. For certain uses the wire reinforcement may be omitted from the back and a fabric which may consist of either cloth or paper substituted therefor upon which nailing strips may be secured preferably at somewhat closer intervals than when the wire mesh is used. This structure 70 is indicated in Fig. 7 in which 19 is the fabric backing and 20 are the reinforcing nailing strips.

75 For greater strength, the reinforcement 1 may be folded at the edge of a board outwardly toward the surface and then at an angle inward as indicated in Fig. 8, the folded fabric preventing any possibility of cracking away pieces of the plastic material when nails are driven into a support 80 through this folded edge.

85 The nailing strips are not necessarily flat but may be ribbed as indicated in Fig. 9 to provide additional rigidity, or they may have any other suitable transverse section, the essential features being that they shall 90 have sufficient strength, that they shall be substantially inextensible in the direction of their length, that they shall be of sufficient width to receive a nail readily and that they 95 shall not be too resistant to the point of a nail to prevent it being easily driven therethrough. The strips will be of a thickness adapting them to be severed by an ordinary wood saw.

100 In practice the boards will be made thirty-two inches wide and about twenty-seven inches high, the joints of all the boards being on as few lines as possible so that the reinforcing strips 12 can be run along the edges of several boards at a time.

105 In order that a finishing coat may adhere properly to a wall board there must be a certain "suction." In other words the rough coat or wall board must be sufficiently porous to absorb some of the moisture from the finishing coat. If a rough coat or plaster board is too porous the water will be withdrawn from the finishing coat so rapidly that not enough will remain for proper hydration of the gypsum. If the rough coat 110 or plaster board is not sufficiently porous, the finishing coat will set as a separate layer with very little adhesion to the rough coat or plaster board. In either case the finishing coat will be likely to crack and fall off.

115 To secure the proper adhesion, the degree of suction of the present wall board is regulated by the use of a size of casein or other suitable material applied to the surface of the wall board.

120 Wall boards constructed as described herein may readily be sawed to fit spaces of smaller dimensions than those of the boards. The texture is such that nails will penetrate the board without cracking it and a finishing 125

130

coat applied to the surface will adhere as firmly as to the ordinary rough coat of plaster.

By the use of this board wooden and metallic lathing are dispensed with and the time required for the application of the boards is much less than that needed to put on lathing and the rough coat of plaster.

Furthermore, the undesirable moisture and dirt unavoidable in putting on the ordinary rough coat is done away with by the use of this factory-made rigid fireproof building material. The finishing coat consisting of gypsum, lime and asbestos flour, is much more fireproof than the ordinary plaster finishing coat. It forms an excellent base for paint and other decorative liquid compositions.

This application is a division of application Serial No. 493,921, filed August 20, 1921, the parent application being limited to the arrangement of the strips 12 at the abutting edges of the panels.

It will be obvious that many variations and modifications may be made in the structure and compositions herein described and I do not therefore wish to be limited to the exact details mentioned, but desire to claim my invention in any of its forms or modifications within the legitimate and valid scope of the appended claims.

What I claim is:—

1. A board comprising a metal fabric backing, a series of metallic strips secured to the backing and having projecting members and a plastic composition body interlocked with said projecting members.

2. A board comprising a metal fabric backing, a series of metallic nailing strips secured to the backing and having projecting members, and a substantially fireproof plastic composition body engaging the projecting members.

3. A board comprising a metal fabric backing, a series of metallic nailing strips spaced apart and secured to the backing, said strips having projecting members and a plastic composition body interlocked with said members.

4. A board comprising a fabric backing, a series of metallic strips adjacent to the backing and having projecting members, and a plastic composition body engaging the members.

5. A board comprising a fabric backing, a series of metallic strips adjacent to the backing and having projecting members, a plastic composition body engaging the members, and a secondary reinforcing fabric adjacent to the surface remote from the metallic strips.

6. A board comprising a fabric backing, a series of metallic strips secured to the backing and having projecting members, a plastic composition body engaging the mem-

bers, and a secondary reinforcing fabric adjacent to the surface remote from the metallic strips.

7. A board comprising a metal fabric backing, a series of metallic nailing strips extending transversely of the board, a body consisting of a substantially fireproof plastic composition, and a secondary metallic reinforcing fabric adjacent to the surface remote from the fabric backing. 75

8. A board comprising a fabric backing adjacent to one surface, a series of metallic nailing strips extending transversely of the board and having projecting members, a body consisting of a substantially fireproof plastic composition interlocked with said projecting members and having a secondary reinforcing fabric adjacent to its outer surface remote from the fabric backing, and a layer of rough gypsum forming said outer surface. 80

9. A board comprising a metallic backing fabric, a series of metallic nailing strips arranged transversely of the board and secured to the backing, a body consisting of a plastic composition of asbestos and plaster, and a secondary fireproof reinforcing fabric adjacent to the surface of the board, the plastic composition extending through the fabric to receive a surface coating of plastic material. 90

10. A board comprising a plastic composition body, a metallic fabric backing, and a series of flat metallic strips adjacent to the backing within said body and capable of perforation by a nail. 100

11. A board comprising a plastic composition body having metallic nailing strips adapted to receive a nail at any point throughout their length, and a reinforcing backing adjacent to said strips, the nailing strips being secured to the backing. 105

12. A board comprising a metallic backing fabric, a series of metallic nailing strips arranged transversely of the board, a body consisting of a plastic composition of asbestos and plaster, and a secondary fireproof reinforcing fabric adjacent to the surface of the board, the plastic composition extending through the fabric to receive a surface coating of plastic material. 110

13. A board having a nailing strip therein extending transversely thereof and adapted to receive a nail at any point throughout its length, said board having upon its surface a line located substantially opposite the central axis of said strip. 120

14. A board comprising a plastic composition having a series of nailing strips extending transversely of the board adjacent to one surface and a fabric reinforcing strip extending longitudinally of the board at substantially right angles to the nailing strips and adjacent to the opposite surface of the board. 125

15. A board comprising a plastic composition having a series of flat tension members extending transversely thereof adjacent to one surface, said members having projecting elements interlocking with the plastic composition.
16. A board comprising a plastic composition having a series of flat tension strips extending transversely thereof adjacent to one surface, said strips being adapted for perforation by a fastening means at any point in their length and having projecting members interlocking with the plastic composition.
- 15 17. A board comprising a plastic composition having a series of flat tension strips extending transversely thereof adjacent to one surface, said strips being adapted for perforation by a fastening means at any point in their length.
18. A board as in claim 19, in which the flat strips are metallic and of a thickness adapting them to be severed by an ordinary wood saw.

In testimony whereof I affix my signature in presence of two witnesses.

CURRY ORA WALPER.
